UNITED STATES PATENT OFFICE.

DANIEL PEHDE, OF WICHITA, KANSAS.

PIANO-HAMMER FELT-SOFTENING TOOL.

Application filed September 27, 1923. Serial No. 665,186.

To all whom it may concern:

Be it known that I, DANIEL PEHDE, a citizen of the United States, residing at Wichita, in the county of Sedgwick and State of Kansas, have invented certain new and useful Improvements in Piano-Hammer Felt-Softening Tools; and I do hereby declare the following to be a full, clear, and exact description of the invention, such as will enable others skilled in the art to which it appertains to make and use the same.

This invention relates to a tool for "voicing" or softening the felt of piano hammers.

It is aimed to provide an efficient and inexpensive tool of this character operable by relatively movable levers, or one movable with respect to the other, and to actuate rotatable pricking members toward each other.

Another object is to provide a construction in which the turnable pricking members have very efficient bearing and support and in which the operating parts for such members are efficiently guided and protected.

Still another object is to provide a construction wherein the link and lever are flexibly connected together and have flexible connection with the gripping members so as to actuate the latter.

Various additional objects and advantages, some of which will be specifically referred to, will become apparent from a consideration of the description following taken in connection with accompanying drawings illustrating an operative embodiment.

In said drawings:—

Figure 1 is a view of the tool in front elevation;

Figure 2 is a view thereof in edge elevation;

Figure 3 is a sectional view on a slightly enlarged scale and taken substantially on the line 3—3 of Figure 2;

Figure 4 is a fragmentary sectional view taken on the plane of line 4—4 of Figure 3, and

Figure 5 is a section taken on line 5—5 of Figure 1.

Like reference characters designate like or similar parts in the different views.

In reducing the invention to practice, operating handles are provided as at 10 and 11. The handles 10 and 11 may be of any approved shape and the former at the work end has spaced side plates 12 integral with it. Handle 11 is pivoted as at 13 to the

plate 12 and has a free inner end portion 14 operable between said plates. One of the handles, for instance the handle 10, has a stop pin 15 projecting therefrom to limit pivotal movement of the handle 11 with respect thereto and the latter may be notched or recessed as at 16 in order to receive the distal end of said pin. A leaf spring 17 may be fastened to the handle 10 and at its free end engage the handle 11 as in a groove 18 thereof, so as to urge the handles 10 and 11 into separated relation at their prickers or pricking ends.

Integral with the plate 12 are lugs 19 having round surfaces as at 20. Spanning the pairs of lugs 19 and rigidly fastened to said lugs are stub shafts or pins 21 on which gripping members 22 are journaled. Prickers 22 are generally cylindrical and have end extensions or flanges 23 integral therewith whose inner surfaces are arcuate and in direct bearing contact with the surfaces 20. Said pricking elements 22 are provided with series of teeth or spurs as at 24.

A short link 25 at 26 is pivotally connected to the end 14 of the handle 11 and at 27 is pivotally connected to a link 28 disposed intermediate the plates 12 and pivoted on a pin 29 bridging said plates. A pitman 30 is pivoted to the portion 14 and to one of the pricking elements 22 while a similar link 31 is pivoted to the link 28 and the other pricking element 22.

In operation, with the parts normally in the position shown in Figure 1 and held in that relation and urged to that position by the spring 17, the handles 10 and 11 are adapted to be grasped by the operator with the teeth 24 arranged in pricking engagement with the felt of a piano hammer and compressed which through the movement of handle 11 on its pivot and the movement of the link 30 corresponding therewith, causes the links 30 and 31 to turn the pricking elements 22 part of a revolution and into effective pricking relation with the said felt, thus pulling the felt in order to soften it and to thus result in "voicing" the piano. After such an operation, the pressure on the handles 10 and 11 is released whereupon the spring 17 restores the same to normal position.

Particular attention is called to the exceedingly efficient support and bearing for the pricking bearings due to the augmentation of their mounting on the shafts 21, by

the bearing engagement of their flanges 23 with the curved surfaces 20 of the lugs 19.

I claim as my invention:—

- 5 1. A tool for softening piano hammer felts having turnable pricklers, and means to operate said pricklers toward each other and with respect to the same hammer.
- 10 2. A tool for softening piano hammer felts having pricklers provided with prick-
ing spurs, and lever means operable to move
said pricklers toward each other and with
respect to the same hammer.
- 15 3. A tool of the class described having a
handle provided with plates, shafts carried
by said plates, pricklers mounted on said
shafts, a second handle, said second handle
being movable relatively to said first men-
tioned handle, and means operable through
movement of the second mentioned handle
20 to move said pricklers toward each other.
- 25 4. A tool of the class described having a
handle, pricklers mounted by said handle, a
second handle, said second handle being
movable as a lever with respect to said first
mentioned handle, a link pivoted to the
second mentioned handle and the first men-
tioned handle, and means to operate the
pricklers toward each other through move-
ment of the second mentioned handle and
30 link.
- 35 5. A tool of the class described having a

handle provided with base plates, lugs on
said plates, shafts carried by said lugs,
pricklers journaled on said shafts, a second
handle, said second handle being pivoted to
35 said first mentioned handle, a link pivoted to
said second mentioned handle and said first
mentioned handle being located intermediate
said plates, and pitman connections between
the second mentioned handle and links and
40 said pricklers.

45 6. A tool of the class described having a
handle provided with base plates, lugs on
said plates, shafts carried by said lugs,
pricklers journaled on said shafts, a second
handle, said second handle being pivoted to
45 said first mentioned handle, a link pivoted to
said second mentioned handle and said first
mentioned handle being located intermediate
50 said plates, pitman connections between
the second mentioned handle and links and
said pricklers, said lugs having curved sur-
faces, and said pricklers having curved sur-
faces in bearing contact with the first men-
tioned curved surfaces.

55 In testimony whereof I affix my signature
in presence of two witnesses.

DANIEL PEHDE.
